UNITED STATES PATENT OFFICE.

FREDERIC L. THOMPSON, OF NEW BEDFORD, MASSACHUSETTS, ASSIGNOR TO
THE PAIRPOINT MANUFACTURING COMPANY, OF SAME PLACE.

DESIGN FOR A METALLIC PATTERN-STRIP.

SPECIFICATION forming part of Design No. 22,737, dated August 22, 1893.

Application filed March 31, 1893. Serial No. 468,570. Term of patent 7 years.

To all whom it may concern:

Be it known that I, FREDERIC L. THOMPSON, a citizen of the United States, residing at New Bedford, in the county of Bristol and State of 5 Massachusetts, have invented and produced a new and original Design for a Metallic Pattern-Strip, of which the following is a specification, reference being had to the accompanying drawing, in which I show my new design 10 for a pattern-strip.

The leading feature of my design consists in scroll work combined with blossoms to form the band or border herein shown.

A is the ornament or pattern, made up of a 15 scroll a , blossom a' , scroll a^2 extended into a coiled scroll a^3 , followed by a blossom a^4 , from which springs the base of a feather-like scroll

a^5 , the tip of which is directly opposed to the tip of the scroll a^6 , which is followed by blossom a^7 , which is followed by a scroll a^8 , the 20 stem portion a^9 of which passes at one side of the blossom a^{10} , the butt end portion of this scroll being coiled at a^{11} . This scroll is followed by a blossom a^{12} , which is followed by scroll work a^{13} , in turn followed by a blossom a^{14} .

What I claim is—

The herein shown and described design for a metallic pattern strip.

FREDERIC L. THOMPSON.
